UNITED STATES PATENT OFFICE.

CHARLES S. BRITTON, OF CLEVELAND, OHIO.

CARBON-MACHINE.

SPECIFICATION forming part of Letters Patent No. 511,751, dated January 2, 1894.

Application filed October 18, 1892. Serial No. 449,222. (No model.)

To all whom it may concern:

Be it known that I, CHARLES S. BRITTON, a citizen of the United States, residing at Cleveland, in the county of Cuyahoga and State of Ohio, have invented certain new and useful Improvements in Carbon-Machines; and I do hereby declare the following to be a full, clear, and exact description of the invention, such as will enable others skilled in the art to which it appertains to make and use the same.

In the modern practice of making electric light carbons, a mold is employed which consists of a bottom plate having a series of half round grooves, a top plate having a series of corresponding grooves, and removable sides which when in place fit closely against the ends of the plates. A measured quantity of the carbon mixture is placed in the mold,—that is on the bottom plate within the sides. The mold is placed in a furnace where the mixture is heated until it becomes sufficiently plastic, when the top plate is put on and the mold is carried to a hydraulic or other powerful press, in which the carbons are molded by the pressure. It is necessary to make the outside frame or sides very heavy in order that they may withstand the pressure of the carbon at the ends of the grooves due to the action of the press. It is customary to construct the outside frame in such manner that it may be easily separated from the plates, and this is done for two principal reasons,—first, to facilitate the removal of the top plates, and second, to free the ends of the grooves so that the carbons may be pushed lengthwise until their ends project beyond the bottom plate whereby a thin flat board may be placed under these ends and all the carbons lifted and removed together by sliding the board under them. By any other method of lifting the carbons from the mold there is great danger of bending or breaking them. This method of procedure involves the frequent lifting and carrying of the very heavy molds and is therefore objectionable. At the same time it is slow compared with the method of procedure with the mechanism hereinafter described, and likewise involves the employment of more labor.

The purpose of my invention is to provide

an apparatus with which electric light carbons may be made more easily and rapidly and at less expense than with the mechanism and by the methods heretofore in use; and my invention consists in the construction and combination of parts hereinafter described and pointed out definitely in the claims.

In the drawings, Figure 1 is a side elevation of my improved apparatus. Fig. 2 is a plan view thereof; and Fig. 3 is a sectional view on line 3—3 of Fig. 1.

Referring to the parts by letter, A represents one of the mold frames. It has a bottom *a'* and four sides *a*.

B represents a plate which has a series of parallel half round grooves in its upper surface extending from one end to the other. This plate fits into the frame with a sliding fit; that is it fits as closely as it can and be adapted to be moved up and down in said frame. When this plate rests on the bottom *a'*, the sides, *a*, extend above its top surface. In the apparatus shown eight of these molds are employed. To the frame of each mold four links C are pivoted,—two at each end; and these links are pivotally connected with similar links which are secured in like manner to the adjacent molds. The links and molds connected as described form an endless link belt of which every third link is a mold.

D D' represent drums secured respectively to the parallel shafts *d d'*, which are mounted in suitable fixed bearings. The drums as shown are hexagonal, and are so formed to present flat surfaces against which the mold bottom may rest. Between the two drums are placed a furnace E and a hydraulic press F, which are so constructed and arranged that as the chain belt is moved, the molds are drawn through the furnace and then to the press. The distance between the two drums and the furnace and press is such that when one mold is resting on a horizontal face of one drum the next mold is in the furnace, the next one is in the press and the fourth mold is on one horizontal surface of the other drum.

Extending from one drum to the other is a table G on which the molds rest and slide in moving forward. The floor of the furnace is

a part of this table, and so also is the platen of the press.

Projecting from the surfaces of the drum D on which the molds rest are the pins or protuberances d^2 ; and in the bottom a' of the mold frame are holes into which these pins project automatically as the mold moves onto the drum. These pins strike against the under side of the plate B and thereby lift it until its top surface is above the top of the sides of the frame.

H represents a shaft having two worms which engage respectively with worm wheels d^3 in the ends of the shafts d d' . The power to operate the described mechanism is applied to the shaft H. On the shaft are two loose pulleys h h and between them one fast pulley h' . Two belts I I from the same counter-shaft are provided to drive the shaft H.

20 One of the belts is crossed as shown.

J represents a belt shifter by means of which either belt may be moved onto the fast pulley and thereby the shaft H may be driven in either direction.

25 K represents a revolving brush mounted in suitable bearings.

L represents a second revolving brush mounted just above and projecting into an oil receptacle M, the shafts of both brushes 30 being driven by belts from the shaft of one of the drums.

When the several molds are in the position shown in the drawings, a measured quantity of the carbon material is placed in the right hand mold. The next mold to the left is in the furnace where the material therein is being rendered plastic enough to be molded in the press.

In order to hold the heat in the furnace, I 40 provide swinging doors e e pivoted at their top edges (shown by dotted lines in Fig. 1). As the mold enters or leaves the furnace, it pushes back these doors, which, when the mold has passed, swing automatically to place 45 and close the openings. The next mold is in the press by which the carbons are pressed into shape between the plate B and plate N which is permanently fastened to the press, and is provided with a series of half round 50 grooves which correspond with the grooves in the plate B. A pipe n may be employed which surrounds and lies close to the edge of the plate N, and steam may be forced through the pipe, thereby heating the plate N, so that 55 it will not chill the carbon material in the mold when brought in contact therewith.

In order to secure the proper entry of the top plate N into the mold frame, the top of the sides a are beveled outward as shown 60 most clearly in Fig. 3. The left hand mold is on the drum D. The projections d^2 have automatically raised the bottom plate above the level of the sides so that the carbons may be removed in the usual manner. When the 65 several operations above described are com-

pleted, the proper belt is shifted to the fast pulley h' , the drums D D' are revolved until the molds are drawn forward to the next position,—that is to say until the mold just filled is in the furnace, and the mold which was in the furnace is in the press, &c., when the mechanism is again stopped, and the press set in motion. In moving forward, the lower molds, which are returning to the filling point, are upside down; the plates B are kept from falling out by means of the pins b b which are fastened to the frame and project into grooves in sides of the plate B. As a mold moves over the brush K, the plate B is brushed clean, and as it moves over the brush L it is oiled so that the carbon material will not stick to it.

Having described my invention, I claim—

1. In an apparatus for making electric light carbons, an endless link belt, a series 85 of molds arranged at suitable intervals connected in and forming a part of said belt, two drums around which said belt runs and by which it is driven, and mechanism for revolving said drums, combined with a furnace, and a press arranged between the two drums, and a table extending from one drum to the other on which the molds are supported, substantially as and for the purpose specified.

95 2. In an apparatus for making electric light carbons, a series of molds each consisting of a frame and a plate fitted in said frame and having a limited vertical movement therein, links pivoted to said frame, thereby connecting them all into an endless link belt and two drums over which said belt runs, combined with a furnace and a press arranged between the two drums, a table extending from one drum to the other on which 105 the molds are supported and peripheral projections on one of the drums adapted to engage with the plates and thereby automatically lift them with respect to their frames, substantially as and for the purpose set forth.

110 3. In an apparatus for making electric light carbons, a series of molds connected by links and forming with them an endless belt, two parallel drums, and means for revolving them intermittently, combined with a furnace, 115 a press, a table, a revolving cleaning brush, and a revolving oiling brush, substantially as and for the purpose specified.

120 4. In an apparatus for making electric light carbons, a series of molds, links connecting said molds and forming with them an endless belt, two parallel drums and mechanism for revolving them intermittently, combined with furnace doors to said furnace adapted to be opened by the molds and to 125 close automatically when the molds have passed beneath them, and a press,—both press and furnace being arranged between said drums, substantially as and for the purpose specified.

5. In an apparatus for making electric light carbons, a series of connected molds each consisting of a plate B, and a frame having a perforated bottom and the sides a, which fit closely to the edges of said plate, and which are beveled outward at their upper edges, combined with a press and a plate fixed thereto, and mechanism for moving said

molds successively into said press, substantially as and for the purpose set forth. 10

In testimony whereof I affix my signature in presence of two witnesses.

CHARLES S. BRITTON.
